UNITED STATES PATENT OFFICE.

SAMUEL HALLANDER, OF VANCOUVER, BRITISH COLUMBIA, CANADA.

VERTICAL BOILER.

1,406,729.

Specification of Letters Patent. Patented Feb. 14, 1922.

Application filed December 5, 1919. Serial No. 342,679.

To all whom it may concern:

Be it known that I, SAMUEL HALLANDER, a citizen of the Dominion of Canada, residing at Vancouver, in the Province of British Columbia, Canada, have invented certain new and useful Improvements in Vertical Boilers, of which the following is a specification.

This invention relates to a steam generating boiler of the vertical class and having steam generating tubes supplementing the heating surface of the fire box.

The invention is particularly described in the following specification, reference being made to the drawings by which it is accompanied, in which:

Fig. 1 is a front elevation and half section of the boiler.

Fig. 2, a sectional plan on the line 2—2 in Fig. 1, and

Fig. 3, a sectional plan on the line 3—3 in Fig. 1.

The boiler comprises an outer cylindrical shell 2 and an inner concentric fire-box shell 3, which latter is preferably corrugated to afford a more effective heating surface and oppose a better resistance to collapse under pressure.

At the bottom the inner and outer shells are connected together on a base ring 4 which is preferably made of two rings of plate, one of which may be produced as at 5, to form the ash-pit which has the customary door aperture.

These rings 4 are carried upward to reinforce the door aperture 6 of the boiler fire-box at the approximate level of the underside of which is the grate 7.

At a suitable height above the grate 7 the inner fire-box shell 3 has an upwardly projecting circular bulge 8, the reason of which will be explained later.

The upper end of the fire-box shell 3 is inwardly flanged to support an annular steam chamber 9 which is formed by a downwardly convex ring 10 and a similar oppositely convex ring 11, the outer edges of both of which rings are secured to the outer shell 2 of the boiler and the inner edge of both to a cylinder 12 which forms also the uptake from the fire-box.

Between the bulge 8 of the fire-box and the inner part of the lower end 10 of the steam chamber 9, coil tubes 15 extend, the same being arranged in concentric circles, see Fig. 3. These tubes 15 are coiled al-

ternately to right and left hand that they may interlock one with another, as shown in the plan, whereby a larger number of tubes may be introduced and the through current of the furnace gases are more effectively obstructed, that their heat may be better imparted to the water within the tubes.

The lower end 10 of the steam chamber between the flange of the fire-box shell 3 and the outer shell 2 has a series of apertures 16 to provide for the downward circulation of the water induced by the upward circulation through the tubes 15.

To afford access to the tube ends in the fire-box shell hand holes 17 are provided in the outer shell 2 around the bulge 8, and access to the upper ends of the same is afforded by a man-hole 18 in the upper ring 11 of the steam space 9. Provision is also made on this ring for the safety valve at 19 and the customary steam space mountings; while the feed and blow-off connections are made adjacent the base ring 4.

A circular baffle 21 of fire-clay or other refractory material is suspended below the lower end of the uptake to prevent direct access of the flame through the central part and to cause the heated gases to travel among the tubes 15. A shield plate 20 is supported within the uptake to protect the plate where it is in the steam space.

To enable the condition of the fire to be examined, particularly when oil fuel is being used, tubular viewing apertures 23 may be inserted at intervals through the outer and fire-box shells around the upper part of the fire-box, which apertures will be closable in any convenient manner with plugs or the like.

With this construction I am enabled to obtain a higher working pressure with a lighter construction of boiler and one occupying less space than the standard Scotch marine boiler for which it may be considered a substitute. Being of small diameter it can be installed or removed without disturbing the ship's fittings and, if standardized, its cost will compare favourably with boilers of the class which it may be required to replace.

The ineffective horizontal furnace is eliminated and it has no flat surfaces to stay. It has a high steam generating efficiency, will attain its working pressure in a minimum of time and without injury when

so formed, as the form and construction are such that a minimum of stress is imposed by expansion and contraction. It is also economical in the use of fuel and is equally 5 adaptable for use with solid, liquid or gaseous fuel.

Having now particularly described my invention, I hereby declare that what I claim as new and desire to be protected in by 10 Letters Patent, is:

1. A vertical boiler, comprising an outer cylindrical shell, an inner fire box shell, the lower edge of which is secured to that of the outer shell, an annular steam chamber secured within the upper end of the outer shell to the lower end of which chamber the inner fire box shell is connected, the bottom of the annular chamber being apertured between the outer and inner shell 15 attachments, and a series of tubes extending between the lower part of the inner fire box shell and the bottom of the annular steam chamber.

2. A vertical boiler, comprising an outer cylindrical shell, an inner fire box shell the lower edge of which is secured to that of the outer shell which inner shell adjacent its lower end is provided with an inwardly projecting circumferential bulge, an annular steam chamber secured within the upper end of the outer shell to the lower end of which chamber the inner fire box shell is connected, the bottom of the annular steam chamber being apertured between the outer and inner shell attachments, and a series of tubes between the inwardly projecting bulge of the fire box shell and the bottom of the annular steam chamber.

3. A vertical boiler, comprising an outer cylindrical shell, an inner fire box shell the lower edge of which is secured to that of the outer shell, said fire box shell having adjacent the lower end an annular circumferential bulge inwardly projecting from 45 its mean diameter, which mean diameter is maintained above and below the bulge, an annular steam chamber secured within the upper end of the outer shell to the lower end of which chamber the inner fire box shell is connected, the bottom of the steam chamber being apertured between the outer and inner shell attachments, and coiled tubes between the bulge of the fire box shell and the underside of the steam chamber.

4. A vertical boiler, comprising an outer cylindrical shell, an inner fire box shell the lower edge of which is secured to that of the outer shell, said fire box shell having adjacent the lower end an annular circumferential bulge inwardly projecting from 60 its mean diameter, which mean diameter is maintained above and below the bulge, an annular steam chamber secured within

the upper end of the outer shell to the lower end of which chamber the inner fire box 65 shell is connected, the bottom of the steam chamber being apertured between the outer and inner shell attachments, and coiled tubes between the bulge of the fire box shell and the underside of the steam chamber, said coiled tubes being disposed in concentric circles within the cross sectional area 70 within the fire box shell.

5. A vertical boiler comprising an outer shell, an inner shell, a base ring the thickness of which approximates that of the plates from which the boiler is made and on which the lower ends of the outer and inner shells are secured, said boiler having a fire door aperture, said base ring being 80 produced upwardly and carried around the fire door aperture to reinforce it and being projected downwardly below the boiler shell plates to form the ash pit.

6. A vertical boiler comprising an outer cylindrical shell, a base ring, an inner fire box shell, the lower end of which is secured to said base ring, and an outer shell, an annular steam chamber formed of two outwardly convexed annular ends, the outer 90 edges of which are secured the required distance apart within the upper end of the outer shell, an inner shell to which the inner edges of the annular ends of the steam chamber are secured, the upper edge of the 95 inner fire box shell being connected to the lower annular end of the steam chamber, which end is apertured between the inner and outer shells, and coiled tubes extending from adjacent the lower end of the fire 100 box shell to the lower end of the steam chamber.

7. A vertical boiler, comprising an outer cylindrical shell, an inner fire box shell the lower edge of which is secured to that of the outer shell, said fire box shell having adjacent the lower end an annular circumferential bulge inwardly projecting from 105 its mean diameter, which mean diameter is maintained above and below the bulge, an annular steam chamber secured within the upper end of the outer shell to the lower end of which chamber the inner fire box shell is connected, the bottom of the steam chamber being apertured between the outer and inner shell attachments, and coiled tubes between the bulge of the fire box shell and the underside of the steam chamber, said coiled tubes being disposed in concentric circles within the cross sectional area 110 enclosed within the fire box shell, the adjacent coils in each ring being right and left alternately with the coils interprojecting.

In testimony whereof I affix my signature.

SAMUEL HALLANDER.
